UNITED STATES PATENT OFFICE.

EARL B. STALEY, OF SEATTLE, WASHINGTON.

MULTIPLE-COMPARTMENT TANK.

Application filed January 18, 1927. Serial No. 161,762.

My invention relates to multiple compartment tanks and the method of making the same.

The object of my invention is to provide such a tank and to construct the same in a manner which makes a strong construction and one which is simple and easily made, whereby its cost may be kept low.

The invention resides chiefly in the manner of placing and securing the intermediate partitions, that is, the partitions which lie between adjacent compartments, and still more particularly to such partitions as are extended below the tank outline to serve as bolsters or supporting webs.

The construction of a tank in which my invention has been incorporated has been shown in the accompanying drawings, and the construction thereof will be described in the following specification; the novel features and those upon which I desire a patent will then be defined by the claims.

Figure 1 is a longitudinal vertical section through a tank made in accordance with my invention;

Figure 2 is a transverse section of the same tank taken adjacent to and looking toward an intermediate partition of the type to which my invention particularly applies;

Figure 3 shows in perspective a tank shell at that point in its construction, in which it has been prepared for the reception of the partition, the partition ready for insertion being also shown.

The tank, as shown in Figure 1, has an outer shell 1, heads 2 and 20, and transverse partitions 3 and 4. The contour of the tank in transverse section is shown as being elliptical, but may be any other suitable shape without affecting my invention.

With tanks of this type, when mounted upon trucks, it has become common to extend certain of the transverse webs, or heads, well below the shell to function as bolsters or supporting webs. The outline of such a web is shown in Figure 2, in which the area 40 represents the part of a partition plate which is outside of and below the tank shell. The end heads 2 and 20 are also shown as having similar bolster-forming extensions.

In securing the ends 2 and 20, it is possible to conveniently weld these to the shell by working outside of the shell. It is also possible to easily secure the partition 3 by welding inside the shell, as no part of it is with-

out the shell or serves as a carrying bolster.

In making the tank shell 1, I prefer to make this of the full length of the tank, or at least of a length which extends the full distance between the heads 2 and 20. To insert the partition 4, I cut with a torch a slot 10 through the shell, extending entirely about the lower half of its circumference. This slot is of a width to properly receive the partition. Such partition is then inserted in place by passing through the slot and welded in place. The upper half of the weld is made from within the tank shell, and the lower half from without the shell.

This method of inserting the intermediate plates leaves the upper half of the tank shells intact and extending as a single sheet from end to end. It is believed that this makes a somewhat stronger structure than even a good welded job.

To further stiffen and strengthen the tank, I incorporate two tubes 5, one at each side, and extending through the bolsters 40, to which they are secured by welding, so as to be an integral structural part of the job. These may also be used to store delivery hose and like objects.

What I claim as my invention is:

1. A tank comprising a shell having a transverse slot cut therein at a location between its ends, said slot extending over substantially the lower half of its circumference, and a partition inserted through said slot and welded to the shell throughout its circumferential extent to thereby close said slot.

2. The method of placing partitions in tanks which consists in cutting a circumferential slot at a location where the partition is desired, said slot having a circumferential extent sufficient to permit insertion of the partition from without; inserting the partition through said slot and welding it to the tank shell to thereby make a tight joint.

3. A tank comprising a shell, heads which extend below the tank to form bolsters, a transverse slot cut in said shell at a location between its ends, said slot extending over substantially the lower half of its circumference, and an intermediate partition which passes through said slot, said partition having an integral portion forming a similar bolster, said partition being welded to the tank wall throughout its circumference.

4. A tank comprising a shell integral from end to end, and a transverse partition secured

therein intermediate its ends, and having an integral bolster projecting through and below the under side of said shell.

5. A tank comprising a shell integral from end to end, heads secured thereto at its ends, and having integral downward extensions forming bolsters, and a transverse partition secured in said shell intermediate its ends, and having an integral bolster projecting 10 through and below the under side of said shell.

6. A tank comprising a shell integral from end to end, heads secured thereto at its ends, and having integral downward extensions 15 forming bolsters, and a transverse partition secured in said shell intermediate its ends, and having an integral bolster projecting

through and below the under side of said shell, and longitudinal stiffening means integrally joined to the several bolsters. 20

7. A tank comprising a shell integral from end to end, heads secured thereto at its ends, and having integral downward extensions forming bolsters, and a transverse partition secured in said shell intermediate its ends, 25 and having an integral bolster projecting through and below the under side of said shell, and longitudinal stiffening tubes extending through the intermediate bolster, and secured in the several bolsters. 30

Signed at Seattle, King County, Washington, this 30th day of December, 1926.

EARL B. STALEY.
